[57] CLAIM

The ornamental design for a plant-sprouting postcard, as shown and described.

DESCRIPTION

FIG. 1 is a bottom perspective view of a plant-sprouting postcard showing my new design;

FIG. 2 is a top perspective view thereof showing the seeds in broken lines for illustrative purposes only and forming no part of the claimed design;

FIG. 3 is a top perspective view thereof, showing a sprouting plant in broken lines for illustrative purposes only and forming no part of the claimed design;

FIG. 4 is a reduced scale bottom plan view thereof;

FIG. 5 is a front elevational view thereof;

FIG. 6 is a top plan view thereof;

FIG. 7 is a rear elevational view thereof;

FIG. 8 is a left side elevational view thereof; and,

FIG. 9 is a right side elevational view thereof.
